UNITED STATES PATENT OFFICE.

BERNARD COOK, OF ROANOKE, VIRGINIA.

DRAFT RIGGING.

Application filed July 5, 1918. Serial No. 243,373.

To all whom it may concern:

Be it known that I, BERNARD COOK, a citizen of the United States, residing at Roanoke, in the county of Roanoke and State of Virginia, have invented certain new and useful Improvements in Draft Rigging; and I do hereby declare the following to be a full, clear, and exact description of the invention, such as will enable others skilled in the art to which it appertains to make and use the same.

The invention relates to draft rigging for railway cars, and more particularly to a method and means whereby the lost motion between the various parts of the draft rigging mechanism, caused by the tremendous shocks and blows of service, may be taken up without modification or reconstruction or renewal of the movable parts of the draft rigging.

One of the principal objects of my invention, broadly stated, is to provide means easily attachable to the draft rigging mechanism for eliminating lost motion. To this end, that portion of the invention comprises a shim, block or plate which may be interposed between two relatively movable parts of the draft rigging, whereby the lost motion between the said parts is removed, the said shim, block or plate being so constructed as to be readily attachable to the draft rigging and of simple construction and inexpensive to manufacture. The other portion of my invention has for its object to follow such a procedure or method in taking up lost motion as will give good results when done by the ordinary car repair man without expert draft gear knowledge, and as will also be quickly and easily accomplished and will give a complete restoration of the worn parts.

Before describing my invention in connection with the specific embodiment thereof which has been selected for the purpose of illustration, attention is called to the effect lost motion has on the efficiency of draft rigging. Owing to the construction of railway cars and the necessity of limiting the separation between two cars of a train, the longitudinal movement of the couplers in either direction from normal has been limited to approximately three inches as a maximum. Within this limited movement all draft riggings must and are de-

signed so as to develop their maximum capacities, hence lost motion in any one of the parts of the draft rigging mechanism whereby a portion of the movement of the coupler unresisted reduces the capacity of the draft rigging. And not only is the capacity of the frictioning mechanism reduced by lost motion between the parts, but the lost motion between the parts permits the parts to move so as to produce therebetween a slap or hammer blow which causes rapid deterioration in the metal and results in frequent failure of the parts with disastrous results to the cars.

In the drawings,

Figure 1 is a view partially in longitudinal section and partially in side elevation illustrating the invention applied to a draft rigging.

Figure 2 is a view showing in side and front elevation a shim designed for application to a coupler, and

Figure 3 is a view showing in side and front elevation a shim designed for insertion between the yoke and a stationary part of the car framing.

Throughout the specification and drawing like parts are designated alike.

Referring now to the disclosure, 1 designates one of the car center or draft sills, 2 the end framing, 3 the floor or cover plate, 4 the angle plate which serves to connect the end framing and the said cover plate.

The coupler 5 is connected to the yoke 6 by means of a transversely extending key 7. Interposed between the rear end of the coupler and the closed end of the yoke is the cushioning mechanism or draft gear proper, which may comprise a front follower 8, a rear follower 9, and a combined friction and spring mechanism 10. In the drawings there is illustrated a well known type of friction mechanism which comprises a plurality of wedging friction blocks 11 and 12, a wedging ring 13, and a spring casing 14. It is here pointed out that the particular form of cushioning mechanism does not form a part of the novel arrangement and hence the invention is not limited to this or any other particular type of cushioning mechanism.

To maintain the cushioning mechanism in position between the arms of the yoke 7 and in alignment with the coupler and the back

stop 15, there may be provided a pair of transversely disposed tie straps or draft gear supporting members 16 and 17, respectively. Stops such as 23, are riveted to the faces of the center sills 1 to form a pocket between these stops and the back stop 15 for the draft gear, the front follower 8 seating against these stops 23. While the rear end of the yoke 6 is shown as interposed between the cushioning mechanism and the rear limiting stop 15, yet this is not necessary as the invention is applicable to other forms of rear limiting stop arrangements.

In Figure 1 of the drawings there is shown 15 interposed between the coupler 5 and the front follower a shim block 18. This shim block preferably comprises an angle shaped member one flange of which is adapted to contact with the rear face of the coupler, and the other flange of which is adapted to underlie the coupler and to contact with the lower face thereof. To maintain the shim block in position the lower flange thereof may be perforated, as shown at 19, and a bolt, such as 20 25 19^a is passed through one of the rivet openings in the coupler and through the perforations 19 in the said shim. This shim or block compensates for lost motion between the key and the coupler and yoke which may be 30 caused by elongation of the key slot in either of these members. This is a very common defect in draft rigging, and unless corrected causes a rapid deterioration of the draft riggings due to the slap or hammer blows here- 35 before mentioned.

In order to compensate for the lost motion between the yoke and the back stop 15, there 40 is provided a shim block 20, which also may comprise an angle plate, the right flange of which is adapted to be inserted between the said yoke and backstop. The horizontally 45 disposed flange being adapted to underlie the lower face of the rear tie strap 17 and to be connected thereto by the rivets 21 which may, for convenience, be countersunk in the said 50 plate 17. The upper end of the shim 20 is preferably provided with a tapered portion 22 so that the same may be driven into place.

It is to be understood that while the drawings 55 illustrate a draft rigging having a shim applied to the coupler and a shim also applied between the backstop and yoke that the invention is not limited to this double application, since the application of a shim block such as disclosed and described in either of the locations may compensate for all lost motion which the particular draft gear has developed.

In lining up draft riggings the first step 60 is to pull the coupler 5 forward until the key 7 is in contact with the rear of the slot in the coupler and with the front of the slots in the yoke 6; also until the yoke is in contact with the rear of follower 9 and until the draft gear and front follower 8 are all drawn up with-

out lost motion against the front stop 23. The liner 18 of the proper thickness is then inserted between the butt of the coupler and the draft gear or front follower and another liner 20 is inserted between the yoke on the rear of the draft gear and the rear limiting stop 15. This method takes up in a practical manner all of the slack and can be followed by unskilled workmen and without removing the gear or the main parts of the attachments. 75

Having now fully described my invention, although it is to be understood that the terms employed are to be taken in their descriptive and not their limiting sense, since what I claim and desire to secure by Letters Patent is:

1. In a draft rigging the combination with a coupler, a yoke, of cushioning mechanism including a follower seated within the said yoke, a transversely disposed key connecting said yoke and coupler, and means for taking up lost motion between said yoke and coupler, said means comprising a member connected to the said coupler and movable therewith and inserted between said coupler and the said follower. 85

2. In a draft rigging a shim for taking up lost motion, said shim comprising an angle plate one flange of which serves as means for connecting the said shim to a draft rigging and the other flange being insertible between two relatively movable parts of the said draft rigging. 95

3. In a draft rigging, a coupler, a yoke, a key connecting the same, a cushioning mechanism within the yoke and to the rear of the coupler, and means for compensating for wear between the key and the yoke and coupler, said means being interposed between the coupler and cushioning mechanism, and adapted to normally contact both of said elements. 105

4. The method of compensating for lost motion in the draft rigging of railway cars of the type wherein the coupler abuts the draft gear and the latter is contained within a pocket having front and rear limiting stops and in which a pulling yoke connects the coupler and draft gear, the same consisting of drawing the coupler ahead to the point at which all of the slack will be accumulated and at which point the draft gear will be arrested by the front stops, and then applying liners of the proper thickness to fill the gap between the butt of the coupler and the draft gear and between the rear of the draft gear and the rear limiting stop. 115 120

5. The method of compensating for lost motion in the draft rigging of railway cars of the type wherein the coupler abuts the draft gear and the latter is contained within a pocket having front and rear limiting stops and in which a pulling yoke surrounds the draft gear and is key connected to the 125 130

coupler, the same consisting of drawing the coupler ahead until the key is in contact with the coupler and the yoke and until the yoke is in contact with the gear and the gear in 5 turn with the front limiting stops, then applying a liner of suitable thickness between the rear end of the coupler and the draft gear to fill up the space therebetween, and then lining the front face of the rear limiting stop an amount sufficient to bring the draft gear 10 into contact.

In testimony whereof I affix my signature.

BERNARD COOK.
